ATTORNEY

UNITED STATES PATENT OFFICE

HENRY RITHNER, OF WELLSBURG, WEST VIRGINIA

TILED WALL CONSTRUCTION

Application filed July 9, 1931. Serial No. 549,592.

This invention relates broadly to wall structures, and it has for its primary object to provide an improved and practical tiled wall construction adapted for use in buildings and embodying, in association with a supporting structure, a rigidly mounted backing and a tile facing, said facing being secured in place upon said backing without the use of cement or other material subject to injury by or through the natural forces of expansion and contraction.

A further object is to provide, in a wall construction of the character mentioned, an improved form of metal backing, as also an improved form of tile, said forms being such that the tile may be introduced directly to seated position on the backing rather than by endwise introduction and sliding movement relative to the seating channels of said backing.

In describing the invention in detail, reference is herein had to the accompanying drawing, in which—

Figure 1 is a front elevation of a fragmentary portion of a wall embodying my invention;

Figure 2 is a section on line 2—2, Fig. 1;

Figure 3 is an enlarged front elevation of a tile and a portion of a backing strip on which said tile is mounted;

Figure 4 is a section on line 4—4, Fig. 3, showing the tile in its fully seated position;

Figure 5 is a similar section showing the tile in entering position;

Figure 6 is an enlarged face view of a backing strip; and—

Figure 7 is a section of the same on line 7—7, Fig. 6.

Referring to said drawing, 1 designates each of a plurality of upright wall studs disposed, as ordinarily, in suitably spaced relation. Rigidly attached to said studs, as by nails 2, is a backing composed of a plurality of horizontally disposed narrow strips 3 of light gauge resilient sheet metal, preferably galvanized iron or steel.

Said strips 3, which are made of a width to correspond substantially with at least one dimension of the tiles 4 which they are to carry, may be provided in any suitable length

or lengths, as, preferably, from four to ten feet. Each of said strips, which are mounted in edge to edge abutting relation, is made of shallow trough-like, or channel, form and comprises a substantially flat body and outwardly directed longitudinal edge portions or flanges 5, the latter having materially less width than the thickness of the tiles and being inclined very slightly toward each other, thereby to render the channel of slightly greater width at its bottom than at its open side.

The angles 6 formed between the flanges and the body of the strip 3, instead of being abrupt, possess a regular curvature, substantially as shown, such curvature being designed substantially to correspond with that of the outer seating edges of the tiles 4.

Said tiles, formed of molded vitreous material, preferably glass, which may be provided in various colors and color effects, are made of rectangular shape with a hollow, or socketed, back, thereby not only to decrease the quantity of material required in their manufacture and, consequently, to reduce the weight of the facing composed thereof, but also to provide a socket-enclosing marginal rib 7 of relatively small thickness designed to seat upon the flat body of the strip 3.

The edges of the tiles have their surfaces disposed at right angles to the faces therof instead of being inclined to correspond substantially with the inclinations of the flanges 5 of the backing strips 3. Thus, in their seated positions the tiles have their upper and lower edges tightly gripped and frictionally held by the flanges 5 instead of occupying dovetail relation to said strips. Due to the relatively small width of the flanges as compared with the thickness of the tiles, said flanges terminate in a plane located rearwardly from that of the faces of the tiles and, consequently, said flanges are wholly covered and concealed by the applied plastic material 8 employed in closing the joints between adjacent tiles.

The seating rib 7 of each tile has its outer terminal edge shaped to form a curved or rounded nose 9, as shown. Thus, in introducing the tiles within the channels of the

backing strips, each is entered in place, first, by seating its lower edge upon the lowermost of the flanges 5 of the strip, as shown in Fig. 5 of the drawing, and then by forcibly 5 pressing the tile inwardly against the resistance offered by said resilient flanges due to their relative inclinations. The tile is thus sprung into place with the upper of said flanges riding upon the thereby engaged 10 rounded nose 9, and, when in fully seated position, said flanges have become spread to the extent that they occupy positions approximately, if not wholly, at right angles to the flat body of the backing strip, and, therefore, 15 in flat-seating frictional engagement with the top and bottom edges of the tile.

Adjoining tiles carried by each strip are spaced apart a distance corresponding to that between tiles carried by adjacent strips, 20 thereby to render all joints of even or uniform width. Said joints are filled, as ordinarily, with a suitable plastic or cementitious material 8, as shown, to give the structure an even, smooth and sanitary finish. The 25 tiles may be shifted laterally, as may be required, from their initial entered positions to final positions properly spaced relative to adjacent tiles.

It is to be noted that the tiles are in no 30 wise affected by expansion and contraction of materials, which, in the case of tiles embedded in the usual cement base, results in the creation of cracks, fractures and like injury.

Furthermore, it will be understood that, 35 should one or more tiles become broken, cracked, chipped, or otherwise injured, they may readily be removed, as by means of a suitable form of pointed or edged tool, and 40 new tiles substituted therefor, introduction being effected in the manner hereinbefore described and without disturbing adjacent uninjured tiles.

The tiled construction herein described, 45 while designed particularly for use in the walls of bath rooms, kitchens and the like, may likewise be employed in floors and ceilings, as also in other places and structures in which surfaces readily maintainable in 50 a sanitary condition are desirable.

What is claimed is:—

1. In a tiled construction, the combination with a supporting structure, of a backing carried by said structure, said backing consisting of a plurality of independent channel-like strips of resilient sheet metal arranged in parallel relation, each strip including longitudinal edge flanges normally occupying convergently inclined relation the flanges of 55 adjacent strips being engaged with each other and a plurality of molded tiles seated in the channel of each strip with opposite edges thereof 60 yieldingly gripped by said flanges, each tile having its said edges disposed substantially at right angles to its face and hold-

ing the therewith engaged flanges outwardly sprung into approximately parallel planes.

2. In a tiled construction, the combination with a supporting structure, of a backing carried by said structure, said backing consisting of a plurality of independent channel-like strips of resilient sheet metal arranged in parallel relation, each strip including longitudinal edge flanges normally occupying convergently inclined relation the flanges of adjacent 75 strips being engaged with each other, and a plurality of molded tiles seated in the channel of each strip with opposite edges thereof yieldingly gripped by said flanges, each tile having its said edges, except a portion thereof located at and adjacent to the junction of said edges with its seating surface, disposed substantially at right angles to its faces and holding the therewith engaged flanges outwardly sprung into approximately parallel planes, 80 said junction portion being curved to form a rounded entering nose.

3. In a tiled construction, the combination with a supporting structure, of a backing carried by said structure, said backing consisting of a plurality of independent channel-like strips of resilient sheet metal arranged in parallel abutting relation, each strip including longitudinal edge flanges normally occupying convergently inclined relation the flanges of adjacent strips being engaged with each other, and a plurality of molded tiles seated in the channel of each strip with opposite edges thereof yieldingly gripped by said flanges, each tile having its rear face enclosed by a marginal seating rib which is curved to form a rounded entering nose.

4. In a tiled construction, the combination with a supporting structure, of a backing carried by said structure, said backing consisting of a plurality of independent channel-like strips of resilient sheet metal arranged in parallel abutting relation, each strip including longitudinal edge flanges normally occupying convergently inclined relation the flanges of adjacent strips being engaged with each other, and a plurality of molded tiles seated in the channel of each strip with opposite edges thereof yieldingly gripped by said flanges, each tile having its rear face enclosed by a marginal seating rib which is curved to form a rounded entering nose, the said edges of each tile, except at said nose, being disposed substantially at right angles to its face and holding the therewith engaged strip flanges outwardly spread in approximately parallel planes.

In testimony whereof, I affix my signature.

HENRY RITHNER.
